AUTOMATIC CUTOFF VALVE FOR FUEL
BURNERSBoris Douvan, Bayonne, N. J., assignor of one-
half to George J. Kupchik, New York, N. Y.

Application January 7, 1950, Serial No. 137,417

10 Claims. (Cl. 158—134)

1

The present invention relates to an automatic cut-off valve for fluid fuel burners, and more particularly to a valve for gas burners which will close automatically if the burner fails to become ignited after the fuel feed conduit has been manually opened or if the flame is extinguished, but which is retained in its open position by thermostatically controlled means as long as the thermostat is heated by the burner flame.

One object of the invention is to provide a cut-off valve of the type set forth which, after manual opening of the fuel feed conduit, will remain in its open position for a predetermined initial period regardless of the operation of the thermostat, but which will move to its closed position at the end of the initial period unless the burner has been ignited and the thermostat has been brought into operation prior to the end of the initial period.

Another object of the invention is to provide a delay-action automatic cut-off valve for fluid fuel burners which is simple in construction and reliable in operation.

A still further object of the invention is to provide a cut-off valve which can be adjusted to various open positions while the burner is ignited and which is retained in each adjusted open position as long as the thermostat is heated by the burner flame.

According to the invention, these and other objects which will appear more clearly as the specification proceeds are accomplished by the arrangement and combination of elements set forth in the following detailed description, defined in the appended claims and illustratively exemplified in the accompanying drawings, in which:

Fig. 1 is a side elevational view partly in section of one embodiment of the invention;

Fig. 2 is a partial section taken on line 2—2 of Fig. 1;

Fig. 3 is a partial end view of the arrangement shown in Fig. 1 as seen from the right;

Figs. 4 and 5 are detail views of detent elements;

Fig. 6 is a partial side elevation of a second embodiment of the invention;

Fig. 7 is an end elevational view showing parts of the arrangement according to Fig. 6 as seen from the right;

Fig. 8 is a partial elevational view of a third embodiment of the invention;

Fig. 9 is a partial right-hand end view of the construction according to Fig. 8.

2

Referring now to the drawings and first to Figs. 1 to 5, 11 is a conventional gas burner to which gaseous fuel is fed through a conduit 12. A valve casing 13 is inserted into the conduit 12 and contains a rotary valve 14 manually adjustable by means of a handle 15. The valve 14 is provided with a projecting stem 16 having sweated thereon a sector-shaped disc 17 provided with teeth 18 on part of its periphery. A coil spring 19 surrounds the valve stem 16 between the valve casing 13 and the disc 17 and has one end 20 anchored on the valve casing 13 and the other end inserted in a hole of the disc 17, so as to urge the valve 14 to closed position.

15 A cam 21 is mounted loosely on the outer end of the valve stem 16 and held in place by a screw 22. A second coil spring 24, which is weaker than the first coil spring 19, surrounds the valve stem between the disc 17 and the cam 21 and has one end inserted in a hole in the disc 17 while its other end extends into a hole in the cam 21. Thus the cam 21 is urged to an angular position corresponding to that of disc 17.

The cam 21 has a raised portion 23 which registers with the beginning of the toothed portion 18 or disc 17 when the cam 21 assumes its angular position corresponding to that of disc 17.

A bracket 25 is secured to a lug 25a on the valve casing, for instance, by means of screws 26. The cylinder 27 of an oil dash-pot is hinged to the bracket 25 while the piston 28 of the dash-pot is hinged by means of its piston rod 29 to the cam 21.

Pivoted to a support 31 secured to the valve casing 13 are two detents 32 and 33, which are urged against the periphery of disc 17 by small springs 34 and 35, respectively. As can be seen more clearly from Figs. 4 and 5, detent 32 has a downwardly projecting tooth 36 and beyond the tooth a downwardly bent end portion 37, while detent 33, which is also provided with a downwardly projecting tooth 38, has an upwardly bent end portion 39. The detents 32 and 33 are angularly off-set with respect to each other in such a way that tooth 36 of detent 32 cannot engage the toothed portion 18 of disc 17 unless the valve 14 is open to a predetermined extent, while the tooth 38 of detent 33 can engage the toothed portion 18 of disc 17 at positions of the valve 14 corresponding to a lesser opening thereof.

A bracket 40 clamped to the conduit 12 supports inside of the burner 11 a bi-metallic thermostat element 41. The bracket 40 has also pivoted thereto a two-armed lever, one arm 42 of

which is engaged by the upper end of the thermostatic element 41 while the other lever arm 43 extends below the upwardly bent end 39 of the detent 33.

As shown in solid lines in Fig. 1 and in Figs. 2 and 3, all parts are in the position which they assume when the valve 14 is closed.

The device operates as follows:

When the valve 14 is opened by turning of the handle 15 in counter-clockwise direction, as seen in Fig. 2, the valve return spring 19 is wound. Tooth 36 of detent 32 will engage the toothed part 18 of disc 17 after the valve has been rotated through an angle of at least about 45°. If the handle 15 is then released, the valve will be retained in its open position due to the engagement of the tooth 36 with one of the teeth 18 on disc 17 against the force of spring 19 which tends to return valve 14 to its closed position.

The spring 24 tends to turn cam 21 in the same direction as disc 17, but the movement of cam 21 is delayed by the retarding action of dash-pot 27, 28. In other words, the spring 24 is wound when the valve is opened and unwinds gradually as cam 21 follows the movement of disc 17 with a predetermined delay. Thus, cam 21 cannot reach its operative position and the raised cam portion 23 does not pass under the downwardly bent end portion 37 of detent 32 until a predetermined initial period of about 15 to 20 seconds has elapsed after the opening of valve 14.

If at the end of this predetermined initial period the burner has not become ignited and the bimetallic thermostat 41 has not been heated, the lever 42, 43 is still in its initial position shown in solid lines in Fig. 1 and the lever arm 43 continues to keep the tooth 38 of detent 33 out of engagement with the teeth 18 of disc 17, as shown in Fig. 2. Consequently, when the raised cam portion 23 lifts the detent 32 against the force of spring 34, tooth 36 is disengaged from the toothed part 18 of disc 17 and the valve 14 is returned to its closed position by the valve return spring 19, whereupon the cam 21 is also gradually returned to its initial position by the spring 24.

If, however, the burner has become ignited, the bi-metallic thermostat element 41 will bend and cause a tilting of lever 42, 43 to the position shown in dot and dash lines in Fig. 1, thereby permitting the detent 33 to assume under the force of spring 35 a position in which tooth 38 engages the toothed portion 18 of disc 17. Consequently, when detent 32 is thereafter lifted by the raised cam portion 23, the valve will be retained in its open position by the engagement of detent tooth 38 with the toothed portion 18 of disc 17.

The teeth 18 have on both sides surfaces equally inclined to a radial line passing through the tip of the tooth so that disc 17 and valve 14 can be adjusted to any desired position while the tooth 38 engages the toothed portion 18 of the disc 17, and the valve 14 will be retained in any adjusted open position exceeding a minimum opening necessary for the proper operation of the burner by the cooperation between the tooth 38 and the toothed portion 18 of disc 17.

If the burner flame after once having been ignited, becomes subsequently extinguished for any reason while the valve is still open, the bi-metallic thermostatic element 41 and lever 42, 43 will return to their initial positions shown in solid lines in Fig. 1 and the tooth 38 will be disengaged from the toothed portion 18 of the

disc 17. The tooth 36 is then incapable of re-engaging the teeth 18 either because it is held out of engagement with the teeth by the raised cam portion 23, if the valve is still more than 45° open and the raised cam portion 23 holds the tooth 36 away from the periphery of disc 17 or because the tooth 36 is no longer opposite the toothed disc portion 18 if the valve has been adjusted to a lesser opening. Consequently, the valve will then be returned to its closed position by the spring 19 and the cam 21 will gradually follow.

In the embodiment of the invention illustrated in Figs. 6 and 7, the burner and bi-metallic thermostat are substantially similar to those shown in Fig. 1 and, for this reason, these elements are omitted from Fig. 6.

In Figs. 6 and 7, the gas conduit is designated by the reference numeral 51. 52 is the valve casing. 53 is the valve. 54 is the control handle. 55 is the projecting valve stem. 56 is the toothed disc. 57 is the valve return spring. 58 is the cam rotatable on the valve stem 55. 59 is the spring extending between the disc 56 and the cam 58. 60 and 61 are the two detents which, in this case, consist of blade springs mounted directly on the valve casing 52. 62 is the thermostat control lever arm which cooperates with the free end of detent 61. The position of the various parts shown in full lines in Fig. 6 and in Fig. 7 corresponds to full opening of the valve and burning of the burner flame.

The arrangement according to Figs. 6 and 7 differs from that shown in Figs. 1 to 5 mainly in the omission of the dash-pot and the substitution of an escapement as delay mechanism for the cam 58. For this purpose, cam 58 is provided along part of its periphery with teeth 63 in engagement with a pinion 64 secured to a shaft 65, which latter is rotatably supported in a bracket 66 depending from the valve casing 52. A toothed wheel 67 is mounted rigidly on shaft 65 adjacent to and rigid with pinion 64. A pendulum 68 is loosely mounted on the end of valve stem 55 and rigidly connected with a two-armed lever 69 carrying at its two ends teeth 70 which can engage the teeth on the wheel 67 to hold the latter normally against rotation.

When the valve is opened, springs 57 and 59 are wound and a force is exerted by one tooth of the wheel 67 against one of the teeth 70, causing the pendulum 68 to start swinging. As the pendulum 68 swings back and forth the teeth 70 of lever 69 release and reengage alternately the gear wheel 67 and thus turning of the cam 58 to the point where it raises the detent 60 is delayed for the predetermined initial period. In all other respects, the operation of the device shown in Figs. 6 and 7 is identical with that of the arrangement according to Figs. 1 to 5 and will be understood without further explanation.

In the embodiment of the invention illustrated in Figs. 8 and 9, the valve stem 71 has fixed thereto a toothed sector-shaped disc 72 and loosely mounted thereon a cam 73. The valve return spring is denoted by the reference numeral 74 and the spring which urges the cam 73 to an angular position corresponding to that of disc 72 is denoted by the reference numeral 75. In this embodiment, a single detent 76 is employed which tends to engage, by means of a tooth 77, the toothed portion of the disc 72 when the valve is opened to a minimum extent.

The cam 73 has a raised portion 78 and a recessed portion 79. A thermostat controlled lever arm 80 assumes a position outside of the

path of any portion of cam 73 as long as the thermostat is not heated (see position shown in dot and dash lines in Figs. 8 and 9). Thus, when the burner fails to become ignited prior to the end of the initial period during which movement of the cam 73 to its operative position is delayed by any suitable delay mechanism, as described with regard to Figs. 1 to 7, the raised portion 78 of cam 73 will, at the end of the initial period, lift the detent 76 and permit return of the valve to its closed position under the action of the valve return spring 74. However, when the thermostat is heated by the burner flame prior to the end of the initial period, the lever arm 80 moves from the position shown in dot and dash lines to the position shown in full lines in Figs. 8 and 9 and enters the recessed portion 79 of cam 73, thus stopping the latter from further movement before the raised portion 78 of cam 73 can lift the detent 76 to disengage the tooth 77 from the toothed portion of disc 72 to permit return of the valve to its closed position.

Whenever the burner flame becomes extinguished and heating of the thermostat ceases, the lever 80 returns to the position shown in dot and dash lines in Figs. 8 and 9, thus permitting cam 73 to complete its movement in counter-clockwise direction as shown in Fig. 9. This causes lifting of the detent 76 by the raised cam portion 78 of cam 73 and return of the valve to its closed position under the action of spring 74. The teeth of disc 72 have on both sides surfaces equally inclined to a radial line passing through the tip of the tooth so that ratchet movement of the disc and, therefore, a manual adjustment of the valve to any desired position is possible while tooth 77 is in engagement with the toothed part of disc 72.

It will be understood that other modifications and variations of the invention could easily be designed and that the scope of protection is not to be limited by the examples illustrated and described except as stated in the following claims.

What I claim is:

1. In an automatic cut-off valve for fluid fuel burners, the combination with a valve casing in the conduit through which the fluid fuel is fed to the burner and a manually adjustable rotary valve in said valve casing, of a first rotary element in the form of a disc rigidly secured to said valve and provided with ratchet teeth on at least part of its periphery, a first spring urging said valve to its closed position, a detent arranged to cooperate with the ratchet teeth on said disc to hold said valve in open position, a second rotary element in the form of a cam supported co-axially with and rotatable relatively to said disc and valve, a second spring weaker than said first spring and urging said cam toward an angular position corresponding to that of the disc and valve, said cam having a raised portion for co-operation with said detent when the cam assumes an operative position corresponding to a predetermined opening of the valve so as to release the disc and valve from the detent for return to the closed position of the valve, a delay mechanism operatively associated with said cam to delay movement of the latter from its position corresponding to the closed position of the valve to its operative position for a predetermined initial period after the valve has been opened, a thermostat adapted to be installed adjacent the burner, and means controlled by said thermostat and operative if the thermostat has become heated by the burner flame prior to the

end of said initial period and as long as said thermostat is heated to interfere with the movement of one of said rotary elements so as to prevent release of the valve for return to the closed position.

5. An automatic cut-off valve as claimed in claim 1, in which the valve has a projecting stem, said disc being rigidly secured to said valve stem and said cam being loosely mounted on said valve stem.

10. An automatic cut-off valve as claimed in claim 2, including a valve casing in which said valve is rigidly mounted, said first spring being a coil spring surrounding said valve stem and having its ends secured to said valve casing and said disc, respectively, and said second spring being a coil spring surrounding said valve stem and having its ends secured to said disc and said cam, respectively.

15. An automatic cut-off valve as claimed in claim 1, in which said delay mechanism comprises a hydraulic dash-pot including a cylinder element and a piston element, one of said elements being hingedly secured to the valve casing and the other element being hinged to said cam.

20. An automatic cut-off valve as claimed in claim 1, in which said delay mechanism comprises an escapement geared to said cam.

25. An automatic cut-off valve for fluid fuel burners, the combination with a manually adjustable rotary valve in the conduit through which the fluid fuel is fed to the burner, of a disc rigidly secured to said valve and provided with ratchet teeth on at least part of its periphery, a first

30. spring urging said valve to its closed position, two detents each arranged for cooperation with the ratchet teeth on said disc to hold said disc and valve in open position, a cam supported co-axially with and rotatable relative to said disc and valve,

35. a second spring weaker than said first spring and urging said cam toward an angular position corresponding to that of said disc and valve, said cam having a raised portion for cooperation with a first one of said detents when the cam assumes an operative position corresponding to a predetermined opening of the valve so as to release the disc and valve from said first detent for return to the closed position, a delay mechanism associated with said cam to delay movement of the latter from its position corresponding to the closed position

40. of the valve to its operative position for a predetermined initial period after the valve has been opened, a thermostat adapted to be installed adjacent the burner, and a lever controlled by said thermostat and arranged for cooperation

45. with the second detent to hold said second detent away from the position in which it is capable of engaging the ratchet teeth of said disc when the thermostat is not heated and to move the second detent out of engagement with the ratchet teeth of the disc when heating of the thermostat ceases,

50. while permitting engagement of the ratchet teeth of the disc by said second detent if the thermostat has become heated prior to the end of the initial period and as long as the thermostat remains heated by the burner flame.

55. An automatic cut-off valve as claimed in claim 6, in which the ratchet teeth on the disc have on both sides surfaces equally inclined to a radial line passing through the tip of the tooth

60. so that the disc and valve can be manually adjusted in either direction regardless of the engagement of either one or both detents with the ratchet teeth.

65. An automatic cut-off valve as claimed in claim 6, in which said two detents are angularly

offset with respect to each other in such a way that said first detent cannot engage the ratchet teeth on said disc unless the valve is open to a predetermined extent, while said second detent can engage said ratchet teeth in any open position of the valve corresponding to a lesser opening thereof whenever the thermostat is heated.

9. In an automatic cut-off valve for fluid fuel burners, the combination with a manually adjustable rotary valve in the conduit through which the fluid fuel is fed to the burner, of a disc rigidly secured to said valve and provided with ratchet teeth on at least part of its periphery, a first spring urging said valve to its closed position, a detent arranged to cooperate with the ratchet teeth on said disc so as to hold said disc and valve in any adjusted open position in excess of a predetermined minimum valve opening, a cam supported co-axially with and rotatable relative to said disc and valve, a second spring weaker than said first spring and urging said cam toward an angular position corresponding to that of the disc and valve, said cam having a raised portion for cooperation with said detent when the cam assumes an operative position corresponding to a predetermined opening of the valve so as to release the disc and valve from the detent for return to closed position, a delay mechanism associated with the cam to delay movement of the latter from its position corresponding to the closed position of the valve to its operative position for a predetermined initial period after the valve has been opened, a thermostat adapted to be installed adjacent the burner, and a lever controlled by the thermostat to assume upon heating of the thermostat by the burner flame prior to

5. the end of the initial period a position in the path of a portion of the cam so as to prevent the cam from reaching its operative position while permitting movement of the cam to its operative position and consequent release of the disc and valve from the detent for return to closed position if the burner flame fails to heat the thermostat prior to the end of the initial period or the burner flame is extinguished and heating of the thermostat ceases after the end of the initial period.

10. An automatic cut-off valve as claimed in claim 9, in which the ratchet teeth on the disc have on both sides surfaces equally inclined to a radial line passing through the tip of the tooth so that the disc and valve can be manually adjusted in either direction regardless of the engagement of the detent with the ratchet teeth of the disc.
